UNITED STATES PATENT OFFICE.

HENRY J. BLAKESLEE, OF MARLBORO, CONNECTICUT.

TESTING SWITCH.

Application filed August 22, 1928. Serial No. 301,218.

This invention relates to a switch of the knife blade type which is constructed to facilitate the connection of testing or measuring instruments, such a switch for instance 5 as is adapted to be inserted between an electrical meter and the current supply.

The object of the invention is to provide a simple, compact and convenient combination 10 of a knife blade switch and a jack whereby a plug connected with a testing or measuring instrument may be readily thrust into the jack and that instrument be connected in series with the switch terminals, the arrangement being such that the switch blade must 15 be opened before the jack plug can be inserted, the plug must be withdrawn before the switch can be closed, and the switch must be closed before the cover of the switch can be closed.

20 This object is attained by locating the jack with its members engaged with each other, between the terminals of the switch and with one member of the jack electrically connected with one switch terminal and the 25 other member of the jack electrically connected with the other switch terminal. In normal use, with the circuit closed, the knife blade connects the switch terminals and carries the current as usual. When it is desired 30 to connect a testing or measuring instrument the knife blade is opened and the plug thrust between the jack members, which action places the instrument to which the jack is connected in series with the switch terminals.

35 As the jack members are in contact with each other until the plug is inserted, opening the switch does not interrupt the regular service.

In the accompanying drawings Fig. 1 shows a plan of a switch constructed according to this invention. Fig. 2 shows a side elevation of the switch with the base and cover in section. Fig. 3 is a side view of the switch showing the blade opened and a plug thrust into the jack. Fig. 4 is a diagram illustrating a use of a switch that embodies this 45 invention.

The base 1 of the switch block is made of insulating material, desirably porcelain, of any suitable length depending upon the 50 number of switches that are to be mounted thereon. A cover 2, usually of a similar insulating material as the base, is placed over the base to enclose the switch.

The switch blade 3 of conducting material 55 and provided with a knob or finger piece 4

of insulating material, is held by the pivot 5 between the conducting ears 6 that are fastened to the base by screw 7. The swinging end of the switch blade is adapted to pass into and out of the space between the spring 60 fingers 8 that are fastened to the base by a screw 9.

The jack shown consists of a member that has an upturned limb 10 and a limb 11 at substantially right angles thereto, which latter 65 limb is electrically connected with the blade pivoting ears 6 and is fastened in position by the screws 7 and 13. The screw 13 is provided with a wire clamp 12 and a binding nut 14. The other member of the jack has 70 a downturned finger 15 bent from the upright limb 16 that at its lower end has an angular extension 17 which is electrically connected with the spring fingers 8 and is held in position by the screws 9 and 19. On 75 the screw 19 is a clamp 18 and a binding nut 20. The adjacent members of the jack are bent so that normally they bear against each other, and these members are also slotted to permit the passage through them of the knife 80 blade. The plug, which has a handle 21 and a cable 22 with the required conductors to connect it with the testing or measuring instrument, has conducting plates 23, 24 that are separated from each other by an insulating strip 25.

When a testing or measuring instrument is to be connected the switch blade is opened as shown in Fig. 3, and the terminals of the plug are thrust between the jack members so that current from one switch terminal or binding nut will pass from one jack member through the plug and instrument connected with the plug to the other jack member and other switch terminal or binding nut.

The arrangement described is very compact and parts are simple to make and assemble. The switch blade can be instantly opened and a jack plug inserted for the purpose of connecting a measuring or testing instrument 95 in the path of the circuit normally completed by the switch blade. In Fig. 4 a meter 26, with a series of controlling switches is illustrated, one of which switches is indicated as connected with a measuring instrument 27, such as a rotary standard. When the switch is opened and the plug is inserted in the jack in such an arrangement, the circuit which includes one of the current carrying coils 28 of the meter is through the standard. 100 105 110

There may be any number of these jack switches applied to a block, depending upon the system in which the device is applied.

The invention claimed is:

- 5 1. A switch block comprising a base having circuit terminals, a switch blade adapted to connect and disconnect the circuit terminals, and a jack with one member electrically connected with one terminal and another member electrically connected with the other terminal.
- 10 2. A switch block comprising a base having circuit terminals, a conducting blade pivotally attached to the base and adapted to open and close the circuit between said terminals, and a jack with one member electrically connected with one terminal and another member electrically connected with the other terminal.
- 15 3. A switch block comprising a base having circuit terminals, ears attached to the base and electrically connected with one circuit terminal, spring fingers attached to the base and electrically connected with the other circuit terminal, a blade pivoted between said ears and adapted to swing into and out of contact with said spring fingers, and a jack with one member electrically connected with said ears and another member electrically connected with said spring fingers.
- 20 4. A switch block comprising a base having circuit terminals, a switch blade adapted to connect and disconnect the circuit terminals, and a jack interposed between the circuit terminals with one member electrically connected with one terminal and another member electrically connected with the other terminal, said jack members being slitted to per-

mit the connection and disconnection of the terminals by the switch blade.

5. A switch block comprising a base having 40 circuit terminals, ears attached to the base and electrically connected with one circuit terminal, spring fingers attached to the base and electrically connected with the other circuit terminal, a blade pivoted between said ears 45 and adapted to be engaged with said spring fingers, and a jack interposed between and electrically connected with said ears and fingers, said jack having yieldingly engaged members which are slitted to permit the movement of said blade.

6. A switch block comprising a base, switch terminals attached to the base, a switch blade adapted to connect and disconnect the switch terminals, a conducting spring finger electrically connected with one switch terminal, and a conducting spring finger connected with the other switch terminal, said fingers being normally engaged but adapted to separate and receive a jack plug when the switch is open. 55

7. A switch block comprising a base having circuit terminals, switch terminals attached to the base and electrically connected with the circuit terminals, a switch blade adapted to connect and disconnect the switch terminals, a conducting spring finger electrically connected with one switch terminal and circuit terminal, and a conducting spring finger connected with the other switch terminal and circuit terminal, said fingers being normally 60 engaged but adapted to separate and receive a jack plug when the switch is open. 65
